US00D866625S

(12) **United States Design Patent** (10) **Patent No.:** **US D866,625 S**
(45) **Date of Patent:** **** Nov. 12, 2019**

(54) **TRANSMISSION HOUSING**

(71) Applicant: **Eaton Cummins Automated Transmission Technologies, LLC**,
Galesburg, MI (US)

(72) Inventors: **Gregory Joseph Born**, Battle Creek,
MI (US); **Timothy Scott Smith**, Paw Paw, MI (US)

(73) Assignee: **Eaton Cummins Automated Transmission Technologies, LLC**,
Galesburg, MI (US)

(**) Term: **15 Years**

(21) Appl. No.: **29/595,582**

(22) Filed: **Feb. 28, 2017**

(51) LOC (12) Cl. **15-09**

(52) U.S. Cl.

USPC **D15/149**

(58) **Field of Classification Search**

USPC 15/5, 7, 9, 9.1, 148, 149
CPC .. F16D 2300/26; F16H 57/02; F16H 63/3026;
F16H 2057/087; F16H 2057/02047; Y10T
29/49464

See application file for complete search history.

(57) **CLAIM**

The ornamental design for a transmission housing, as shown and described.

DESCRIPTION

FIG. 1 is a front perspective view of a transmission housing; FIG. 2 is a rear perspective view of the transmission housing;

FIG. 3 is another front perspective view of the transmission housing;

FIG. 4 is another rear perspective view of the transmission housing;

FIG. 5 is a first side view of the transmission housing;

FIG. 6 is a second side view of the transmission housing;

FIG. 7 is a front view of the transmission housing;

FIG. 8 is a rear view of the transmission housing;

FIG. 9 is a third side view of the transmission housing; and,

FIG. 10 is a fourth side view of the transmission housing.

1 Claim, 10 Drawing Sheets
